FLUID POWER CONVERSION APPARATUS

Jules G. Walter, Ridgewood, N. Y., assignor to
 Samco Holding Corporation, New York, N. Y.,
 a corporation of New York

Application April 3, 1946, Serial No. 659,176

3 Claims. (Cl. 121—59)

1

This invention relates to variable speed drives and particularly to a drive employing a fluid pump and motor.

The object of the invention is to provide a drive of this type which will be simple, inexpensive and efficient and which will provide for a progressive, easily controlled variation in the speed of the motor.

Further objects of the invention, particularly in the control and reversal of the operation and the special operative features of the motor pistons engaging a central eccentric, will appear from the following description taken in connection with the accompanying drawings in which

Fig. 1 is a plan view with parts in section on line 1—1 of Fig. 2;

Fig. 2 is a front elevational view with the front plate omitted;

Fig. 3 is a vertical sectional view taken on line 3—3 of Fig. 2;

Fig. 4 is a perspective view in detail of control valve on enlarged scale; and

Fig. 5 is a sectional view illustrating a modified form of engagement between the plungers and eccentric ring.

In the embodiment shown in the drawings, the rotor comprises a shaft 6 (Fig. 3) carrying the rotor head 7 and running in bearings 9 in the extension 11 of the stator casing 10, carried by the base 8, a cover 12 being fastened to the stator casing 10 as shown.

When the motor rotor 7 revolves counter-clockwise (Fig. 2) the fluid passes under pressure in through the passage 13 to the intake distributing chamber 14 and is discharged through the passage 15 from the collecting chamber 16, these passages 13, 14, 15 and 16 being formed in the stator casing 10 as shown.

Between the intake and collecting chambers 14 and 16 are the separating contact areas 17, 18 having grooved arcuate surfaces flush with the inner cylindrical surface 19 of the casing 10. The edge of this cylindrical surface 19 overhangs the outer ends of the radial cylinders 20 to retain the piston plungers 21 in the cylinders and against escape therefrom into the chambers 14 and 16 whenever the centrifugal forces are sufficient to overcome the pressures against the piston head.

The rotor 7 slidingly fits the cylindrical surface 19 and the radially directed inner surfaces 29, 30 (Fig. 3) of the stator 10 and cover 12. Radial cylinders 20 in the rotor are fitted with piston plungers 21, each plunger comprising a cylindrical piston portion 22 and a rounded inner or head end 23 engaging the periphery of a ring 24 running on bearing balls 25 on raceways 26 car-

2

ried by the ring 27 fixed to the cover 12 by the screw bolt 28, the axis of assembly 24, 25, 26, 27 and 28 being offset as shown with relation to the axis of rotor 7 to provide the desired eccentricity.

In the operation of the apparatus counter-clockwise as a motor, fluid pressure is admitted through the passage 13 and distributed by the chamber 14 to the heads 22 of the pistons 21 of the cylinders 20 communicating with the chamber 14. The resultant pressure of the inner rounded heads 23 of the plungers 21 against the offset bearing ring 24, as transmitted through the bearings 25, has a tangential component in the direction of the arrow (Fig. 2) which is maintained throughout the arc of inward movement of the plungers 21. The exhaust or discharge from the motor releases the fluid from the cylinders 20 and the collecting chamber 16 and the passage 15 reducing the pressure against the plungers 21 as they are moved outward by the offset bearing ring 24 during their upward travel in communication with the collecting chamber 16.

As the plungers 21 move inward and outward in their respective cylinders, the rounded heads 23 of the plungers roll slidingly on the periphery of the offset bearing ring 24 due to a progressive shift in their angular position with relation to the axis of the eccentric. The rounded surfaces 30 of the heads 23 readily permit this rolling movement with negligible friction, the offset bearing ring 24 rotating at substantially the same R. P. M. as the rotor 7. The grip of this rolling friction of these heads 23 is sufficient to avoid any substantial slippage between the ring and the plungers.

The resultant rotary torque on the rotor 7 is communicated to the shaft, thus converting the fluid pressure power received at passage 13 into rotary movement of the shaft 6.

A fluid pump 35 to supply pressure for the motor is housed in the pump chamber 36 of the base 8. The supply for pump 35 is provided by vertical intake 37 from sump chamber 38 formed as a hollow reservoir in base 8. The fluid pressure output of pump 35 is delivered through passage 40 to the rear end 41 of central manifold 42 extending to the front (cover plate) end of the housing, and communicating at the front end 50 with the passages 13 and 15 and with the discharge passage 45 opening down into the sump chamber 38.

A cylindrical valve member 47 is rotatably fitted in the manifold chamber 42 and is grooved 55 to provide an annular space 48 leading to the opening 49 into the central hollow bore 50 ex-

tending forward to the passage 51 leading radially outward to the end chamber 53 provided by the arcuate peripheral recessing of the end of member 41 leaving this crescent-shaped pressure supply chamber 53. The opposite side of the end of member 41 is cut away at 55 to form the crescent discharge passage 56.

In the central position of valve member 41 (Fig. 2) both the pressure supply 53 and discharge 56 are out of communication with the passages 13 and 15 to the motor, and then assuming that the pump 35 is running, its pressure fluid passes through passage 40 to chamber 48, opening 49, bore 50 and by-pass 57 in the valve and outlet passage 58 in the base structure 15 to sump chamber 38 and back to the pump. No power is applied to drive the motor.

When the motor is to be driven counter-clockwise (Fig. 2) the valve member 41 is turned counter-clockwise by means on the outer end of the control shaft 59 extending forward from the member 41. The first portion of this valve movement connects pressure chamber 53 to passage 13 and chamber 14 to supply fluid pressure to the piston 21 on the left side of the rotor (Fig. 2) and at the same time discharge chamber 56 of the valve is connected to the passage 15 and chamber 16 to permit outflow of fluid from the cylinders 20 on the right side of the rotor.

The initially applied pressure is low because of the bleeding of the fluid through by-passes 57, 58 into the sump, and as the valve 41 continues to turn, this by-pass relief is progressively choked off until finally the valve opening 57 is entirely out of register with the matching drain 58, whereupon full pressure is applied to the driving side of the motor and the exhaust side is connected freely to the discharge through valve chamber 56 and passage 45 into the sump.

The driving pressure will therefore depend on the position of the valve member 41 and for a given resistance to the motor drive the motor speed will vary with the applied driving pressure. Control of the speed of the motor drive is thus attained by turning of the valve member 41 and this control may be connected up in any desired manner to be actuated automatically by conditions in the driven mechanism or related apparatus.

The direction of rotation of the motor may be reversed by reversing the rotation of the control valve 41 to bring the pressure chamber 53 into connection with passage 15 and the discharge 56 opening from passage 13. The control of the speed acts in the same manner on clockwise rotation (Fig. 2) so that the motor may be driven in either direction at all speeds up to the maximum and the control is continuous throughout.

The pump 35 may be of any desired type and driven through a shaft protruding from the housing in either direction. In the form shown the upper pump gear 61 has a shaft 62 with its rear end in bearings 63 and its front portion protruding out through the front for attachment to the power drive. Other arrangements of the drives and adjustments may be employed, and the relative positions of the pump and the fluid motor may be rearranged as desired.

The combination as shown is simple, compact and inexpensive in manufacture and provides in the single unitary structure all of the elements for the conversion of the power and the gradual continuous control of the output speed 75

of the motor rotor. The piston plungers 21 have no complicating connections or valves and are normally held in contact with the surface of the ring 24 and are retained in their cylinders 5 20 by the overhanging portion of the cylindrical surface 19 (Figs. 1, 2 and 3).

The pressure supply may have a relief bypass 70 from the pressure passage 40 to the sump chamber 38 containing a resilient valve device 71 opening under predetermined excess of pressure to protect the apparatus and permit a fluid flow and circulation from the pump discharge around to the pump intake without passing through the valve and motor parts. The ends of the control member 41 may be packed to retain the pump pressure and have a pressure relief outlet 72, 73 bleeding back any leakage into the sump chamber 38 so that the end of the shaft is protected against the trapping and building up of excessive fluid pressures. A similar relief passage 75 is added to the extension 11 between bearings 9 in order to prevent the building up of excessive fluid pressure.

The showing described is a typical embodiment and various modifications may be made within the scope of the invention. As indicated in Fig. 5 the piston plungers 78 may be provided with extended surface contact with the offset bearing ring 71 by forming the cylindrical seat 79 and rotatably fitting in it the shoe 80 having a segment of its periphery 81 conforming to the arc of the offset bearing ring.

The invention has been shown and described in connection with a specific embodiment, but it is not intended to be confined thereto, the principle of the invention broadly covering the subject matter as set forth in the appended claims.

I claim:

1. A rotary hydraulic machine comprising a driven shaft, a rotor mounted on said shaft in annular formation with radially directed cylinders and pistons freely and independently mounted therein and projecting within said annular formation, a stator housing said rotor and having open-ended intake and exhaust chambers peripherally surrounding said rotor in communication with the outer ends of said cylinders and said pistons, a fixed member eccentrically positioned within said annular formation of said rotor and within the inner ends of said cylinders and having an outer piston-engaging ring running on anti-friction bearings, said pistons having curved end surfaces integral with and in fixed relation to said pistons in pivotal contact with said ring and closely approaching each other in near contact adjacent the said ring and pressing against said ring on application of hydraulic pressure to said piston rotating said rotor and turning said piston about said contacting portion of said curved surfaces as the ring moves with said rotor and piston.

2. A rotary hydraulic machine as set forth in claim 1 in which said curved surfaces are convex and roll on the outer surface of said ring as said rotor rotates.

3. A rotary hydraulic machine as set forth in claim 1 in which there is a slidably convex surface in frictional gripping relation with said ring and mating with a concave surface, said concave surface pivoting said piston around said contact surface to turn said piston in relation to said ring.

JULES G. WALTER.
